WALL STRUCTURE

William Kleitz, Albany, N. Y.

Application December 10, 1931, Serial No. 580,023

2 Claims. (Cl. 72—45)

This invention relates to wall structure and more especially to wall structures of the so-called hollow type.

An object of this invention is an insulated wall which is effective to resist temperature changes and moisture penetration.

According to this invention, the wall comprises outer masonry sections between which is arranged a core of heat and moisture resistant insulated material. The outer sections may be composed of poured concrete, reinforced if desired, or may be composed of stone, brick or other preformed units used in masonry. The core may be composed of preformed slabs of insulating material or may be composed of a body of insulating material poured in liquid form into the space between the sections and allowed to solidify. Where preformed slabs of insulating material are used, they are supported during the construction of the two outer sections by anchors which hold them in spaced relation to such sections. These anchors are eventually incorporated in the finished wall and become permanent reinforcing members. Such a wall structure effectively resists temperature changes and moisture penetration and when used as the exterior wall of a building permits the application directly to its surface of interior finish such as plaster, wall-paper, paint, etc, thus avoiding the use of the usual furring and lathing, hollow brick, terra cotta furring or other interior insulation.

Other objects, novel features and advantages of this invention will be apparent from the following specification and accompanying drawings, wherein:

Fig. 1 is a vertical section through a poured concrete wall, before removal of the forms.

Fig. 2 is a perspective view partly broken away of a finished wall;

Fig. 3 is a section on the line 3—3 of Fig. 1;

Fig. 4 is a section on the line 4—4 of Fig. 1;

Fig. 5 is a vertical section through a modified form of wall structure;

Fig. 6 is an enlarged fragmentary view similar to Fig. 5;

Fig. 7 is a view similar to Fig. 6 of a modified form;

Fig. 8 is a vertical section of a further modification;

Fig. 9 is a perspective view of Fig. 8 partly broken away;

Fig. 10 is an enlarged fragmentary view similar to Fig. 8;

Fig. 11 is a vertical section of a modified form, and

Fig. 12 is an elongated fragmentary section similar to Fig. 11.

The wall structure disclosed in Figs. 1 to 4 is of the poured concrete type. In constructing this wall, a moulding form is used and comprises a pair of plates 10 which are held in place in the usual manner by tie rods 11 equipped with pins 11a which serve to prevent inward movement of the plates. Between the plates 10 are arranged two groups of vertical and horizontal reinforcing rods 12 and also a vertical core 13 of insulating material which is located between the groups of reinforcing rods and is composed of preformed insulated slabs laid edge to edge one on top of the other. The tie rods 11 pass through apertures provided in the bodies of the slabs of insulating material or through apertures formed by co-operating semi-cylindrical recesses in the contacting edges of the slabs. The insulating slabs preferably are of such height that they exactly span the space between different rows of ties and spreaders 11. The width of the slabs may equal the distance between adjacent rows of tie rods or may equal a multiple thereof. This relation of the width of the slabs to the spacing of the rows of tie rods makes easier the locating of the slabs and the fastening of them to the tie rods.

Preferably the insulating slabs are attached to the tie rods 11 by means of wires 14 passed through the insulating slabs near the edges thereof and then firmly wound around the tie rods. The slabs may be additionally supported by means of anchors 15 embedded in the slabs of insulating material or otherwise attached thereto and having their ends wired to the reinforcing rods 12, these anchors being intermediate the tie rods 11. These anchors preferably are embedded in the slab of insulating material when the latter is molded and may be flexible so that they can be bent into contact with the slabs until the slabs are put into actual use.

After the plates 10 and the slabs 13 have been assembled with the tie rods and reinforcing rods, the concrete is poured into the spaces between the plates and the slabs and allowed to set. After the concrete has set, the plates 10 are removed in the usual manner and the projecting ends of the tie rods 11 are broken off, these rods being weakened as at 11b for that purpose. The complete wall then comprises two outer sections of concrete between which is provided a core of insulating material, the core being firmly an-

chored to both concrete sections by the rods 15 and rods 11 which, together with the rods 12 comprise reinforcing means for the concrete sections.

5 The wall structure disclosed in Figs. 5 to 7 consists of a brick section and a concrete section having interposed a core composed of superposed slabs of insulating material. In the construction of this wall, bricks 16 are laid one on the other in the usual manner and bound together by cement. At predetermined intervals tie rods 17 are incorporated into the structure by having one end of the tie rod embedded in the layer of cement between two bricks. The ends of the 10 tie rods are either upturned as shown in Fig. 6 or crinkled as shown in Fig. 7 so that they are securely anchored in the cement. Slabs 18 of insulating material are associated with the masonry unit as it is built. These slabs are provided with 15 anchors 19 which are embedded in the slabs or otherwise firmly attached to the same and may be flexible so that they can be bent into contact with the slabs until the slabs are put into actual use. One end of each anchor is embedded in the 20 layer of cement between superposed bricks, this end being suitably deformed to securely hold it in position. The tie rods 17 may either pass through apertures in the bodies of the slabs or through apertures formed by co-operating semi- 25 cylindrical recesses in the contacting edges of the slabs. The slabs may be firmly secured to the tie rods by means of wires 20 passing through the slabs and having their ends wound around the rods. After completion of the masonry section 30 and the insulating core, a moulding plate 21 is assembled with the tie rods 17 in the usual manner and in spaced relation to the insulating core and concrete is poured into the space thus formed. If the concrete section is to be reinforced, suitable 35 reinforcing rods 23 are assembled with the tie rods and anchors before the plate 21 is set up, these reinforcing rods preferably being wired to the tie rods and anchors. After the concrete has set, the moulding plate 21 is removed and the 40 ends of the tie rods are broken off as previously described. The completed wall then comprises a masonry section and a concrete section between which is provided a core of insulating material, the core being firmly anchored to both 45 sections by the rods 17 and 19 which, together with the rods 23 comprise reinforcing means for the concrete section.

The structure disclosed in Figs. 8 to 10 inclusive consists of two brick sections 24 and 25 between which is arranged an insulating core 26 composed of superposed slabs of insulating material. These slabs are provided with anchors 27 firmly attached thereto. These anchors preferably are embedded in the slabs of insulating 50 material when the same are being molded and the ends are deformed. Both ends of each anchor extend into layers of cement between rows of brick and firmly anchor the insulating core to the wall sections. The insulating core is built up along with the masonry units.

In the modification disclosed in Figs. 11 and 12, the wall structure comprises two brick units 28

and 29, and a core 30 of insulating material which is formed by pouring liquid insulating compound into the space between the masonry units and allowing the same to solidify. Anchors 31 have their ends embedded in layers of 80 cement between rows of brick at different levels and the insulating material solidifies around these anchors so that in the finished wall, the various parts are firmly anchored to each other.

85 Each of the structures above described is effective to resist temperature changes and moisture penetration, thereby permitting the direct application of interior finish to the inner surface of such a wall when used as the exterior wall of a building. Plaster, wall-paper, paint, etc., can be 90 directly applied to such surface, thus dispensing with the use of the interior insulation.

95 The term "masonry" is used in this specification to define concrete structures as well as structures composed of preformed units and is to be so understood whenever it appears in the specification and claims. The word "brick" is used as descriptive of any type of preformed unit. Although the concrete structures are shown as being provided with reinforcing rods, such rods may be 100 dispensed with where load for the wall does not require their use or where the wall is made sufficiently thick that the rods are not needed.

105 It is of course understood that any suitable type of tie rod may be used, there being a large number of satisfactory types of tie rods commercially known. Also, the slabs of insulating material may be installed either with their length running vertically or horizontally and that while wires have been used for securing the slabs of 110 insulating material to the tie rods, other wires and means can be used for that purpose.

I claim:

115 1. A building wall structure comprising a pair of spaced parallel masonry sections, a continuous insulating core interposed between said masonry sections, said core comprising superposed solid plane surface insulating slabs having cooperating 120 opposed recesses in contacting edges, tie rods extending through the apertures formed by said recesses and having their ends embedded in said masonry sections, and wires passing through said slabs adjacent said recesses, the ends of said wires being wrapped around said tie rods to bind the 125 slabs together and to said tie rods.

130 2. A building wall structure comprising a pair of spaced parallel masonry sections, a continuous insulating core interposed between said masonry sections, said core comprising superposed solid plane surface insulating slabs having cooperating 135 opposed recesses in contacting edges, tie rods extending through the apertures formed by said recesses and having their ends embedded in said masonry sections, wires passing through said slabs adjacent said recesses, the end of said wires being wrapped around said tie rods to bind the slabs together and to said tie rods, and anchors having their central portions embedded in said slabs and having their end portions embedded in said masonry sections.

140 WILLIAM KLEITZ.
